(57) **CLAIM**

The ornamental design for a plug adapter as shown and described.

DESCRIPTION

FIG. 1 is a front, right and top perspective view of a plug adapter, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of a second embodiment of a plug adapter.

FIG. 10 is a rear, left and bottom perspective view of the second embodiment of the plug adapter of FIG. 9.

FIG. 11 is a front elevation view of the second embodiment of the plug adapter of FIG. 9.

FIG. 12 is a rear elevation view of the second embodiment of the plug adapter of FIG. 9.

FIG. 13 is a left side elevation view of the second embodiment of the plug adapter of FIG. 9.

FIG. 14 is a right side elevation view of the second embodiment of the plug adapter of FIG. 9.

FIG. 15 is a top plan elevation view of the second embodiment of the plug adapter of FIG. 9; and,

FIG. 16 is a bottom plan elevation view of the second embodiment of the plug adapter of FIG. 9.

The broken lines depict portions of the plug adapter that form no part of the claimed design.

1 Claim, 16 Drawing Sheets
